UNITED STATES PATENT OFFICE.

JEAN V. GIESLER, OF KNOXVILLE, TENNESSEE, ASSIGNOR TO THE FULTON COMPANY, OF KNOXVILLE, TENNESSEE, A CORPORATION OF MAINE.

SAFETY DEVICE.

Application filed March 12, 1923. Serial No. 624,648.

To all whom it may concern:

Be it known that I, JEAN V. GIESLER, a citizen of the United States, and a resident of Knoxville, Tennessee, have invented new 5 and useful Improvements in Safety Devices, which invention is fully set forth in the following specification.

This invention relates to safety devices and, while capable of a variety of uses, is of 10 particular utility when employed with burners using a liquid fuel.

It is customary to supply burners employing a liquid fuel with fluid under pressure, such as air for example, to atomize the fuel 15 or to assist in supporting the combustion of the fuel or both. If the flow of fluid under pressure stops for any reason, such for instance as may occur because of the stopping of the motor of the air compressor, the continuing flow of the fuel will cause the flooding 20 of the burner, with the resultant danger of fire or even explosion. To overcome this difficulty it has been proposed to connect a valve in the fuel line directly to a diaphragm 25 subjected to the pressure of such fluid flowing to the burner, so that the diaphragm will hold the fuel valve open under the action of the pressure, but when there is a drop in the pressure, the fuel valve will be 30 closed by the movement of the diaphragm. Devices of this type, however, possess the grave disadvantage that the fuel valve will be opened immediately that the fluid pressure is restored, so that unless the attendant 35 is present to light the burner immediately, there is still the likelihood of flooding the burner with the resultant danger of fire or explosion. To avoid this latter difficulty, it has been proposed to provide the fuel valve 40 with a weighted lever and to provide the diaphragm subjected to fluid pressure with a detent to cooperate with said lever and hold the fuel valve open while the fluid pressure is maintained, the fuel valve being released by the diaphragm detent upon a decrease 45 in the pressure of the fluid supply; in this case the fuel valve can be opened only by a manual resetting of the device. Devices of this latter character, however, also 50 possess serious disadvantages among which may be noted the fact that the parts of the trip mechanism are likely to become worn or get out of alignment so that they fail to operate satisfactorily; the diaphragm is always 55 subjected to the fluctuating fluid pres-

sures even though the fuel valve is not open; when the fluid pressure is restored, so that the diaphragm is bulged outwardly, it is difficult to reset the trip device, particularly if the fluid pressure is large, because of the necessity of flexing the diaphragm against the fluid pressure acting thereon; there is no positive connection between positively moved parts of the pressure-responsive device and the fuel valve to insure the closure of the latter upon operation of the diaphragm; etc.

It is an object of this invention to provide a safety device of the type under consideration wherein a part which is positively movable with the diaphragm or flexible wall is 70 directly connected to the fuel valve to insure closure of the latter upon failure of the pressure-fluid supply and yet wherein the fuel valve will not be opened by the return of the fluid pressure.

Another object of this invention is to provide a safety device of the type under consideration whereby the use of trip mechanism with its consequent disadvantages may be avoided and yet the fuel valve can be 80 opened only by a manual resetting of the device.

Another object of this invention is to provide a safety device of the type under consideration wherein the source of fluid under pressure is disconnected from the flexible wall for operating the fuel valve upon the closure of the latter.

Another object of this invention is to provide a safety device of the type under consideration wherein the chamber associated with the flexible wall for operating the fuel valve is vented to the atmosphere when it is disconnected from the source of fluid under pressure, to insure that leakage of this fluid 90 into this chamber shall not develop a pressure in said chamber which will open the fuel valve.

Another object of this invention is to provide a safety device of the type under consideration which is simple in construction, which may be readily adjusted to conform with the fluid pressure to be employed with different burners under different conditions, which is easy to manufacture and install, and which is efficient in operation.

Other objects will appear as the description of the invention proceeds.

The invention is capable of receiving a variety of mechanical expressions, one of

which is shown on the accompanying drawings, but it is to be expressly understood that the drawings are for purposes of illustration only and are not to be construed as a definition of the limits of the invention, reference being had to the appended claims for that purpose.

Referring in detail to said drawings, wherein the same reference numerals are employed to designate corresponding parts in both figures—

Fig. 1 is an elevation of a safety device embodying the present invention; and

Fig. 2 is an axial section on an enlarged scale through the fuel valve, the flexible wall and the associated parts.

In the form shown, 1 designates a conduit, such as is commonly employed for conveying a liquid fuel to a burner. Interposed in said conduit is a valve housing 2 of any suitable construction and adapted to be connected to the sections of said conduits by the unions 3. Within the valve housing 2 is a valve 4 of any suitable form provided with a valve stem 5 which projects exteriorly of the housing as shown at 6, and is there suitably connected to a slotted member 7 provided with a threaded extension 8. Said threaded extension 8 is adjustably connected to a threaded sleeve 9 projecting from a plate 10 which bears against, but in most cases need not be connected to, the movable end wall 11 of an expandable and collapsible chamber 12. Said chamber may be of any suitable construction, being shown as formed by a flexible corrugated tubular wall 13, preferably of seamless resilient metal, suitably secured, as by soldering or brazing, to the movable end wall or closure member 11 at one end, and to a stationary, preferably rigid, end wall 14 at its opposite end. Projecting from said stationary end wall 14, and formed either integrally therewith or suitably connected thereto, is a nipple 15 provided with a passage 16 which communicates through the end wall 14 with the interior of the chamber 12. The opposite end of said passage 16 communicates through a valve housing 17 with a conduit 18 which leads from any suitable portion of the pressure fluid system, such for example as a pipe for conveying the fluid, as air, under pressure to the burner to aid in the combustion of the fuel by atomizing the fuel or furnishing a combustion supporting fluid or both. Valve housing 17 contains a valve 19 of any suitable form for opening and closing the connections between this source of fluid under pressure and the chamber 12. In order that leakage of fluid past the valve 19 shall not build up a pressure in the chamber 12, it is also desirable that the chamber 12 shall be vented to the atmosphere when the valve 19 closes said connections between the source of fluid under pres-

sure and said chamber. In the form shown, the valve 19 is tightly but rotatably mounted in a recess in the housing 17 and provided with a passage 20 extending diametrically through the same and a second 70 passage 21 extending at right angles from said passage 20 to the surface of the valve member. The valve housing 17 is also provided with an aperture or port 22 in position to register with the passage 20 when the passage 21 is in communication with the passage 16.

The structure so far described may be mounted in any suitable way. In the form shown a frame 23 is mounted on the bonnet of the valve housing 2 and may be retained thereon in any suitable way, as by clamping the base member 24 of said frame between the bonnet and one or more nuts 25 threaded onto a spindle 26 which projects from the bonnet and has an axial passage therethrough for the valve stem 5. The frame 23 is preferably provided intermediate its length with a portion 27 having a passage 28, in alignment with the valve stem 5, 6 and the threaded extension 8 on the member 7, in which is suitably secured a sleeve 29 provided with an interior bore which affords a sliding fit for the sleeve 9 to guide the valve stem and restrict it to rectilinear movement. In the form shown, the sleeve 29 is exteriorly threaded at one end and held in position by the setscrew 30, and a nut 31 thereon, which engages the top of the frame portion 27, cooperates with this threaded sleeve to adjust the latter so that its upper end will be engaged by the plate 10, when the chamber 12 is expanded, before the valve 4 engages its housing, to thereby relieve the valve stem 5, 6 of the thrust of end wall 11 of said chamber while the valve 4 is held open. The upper portion 32 of the frame 23 is also provided with a passage 33 which receives the nipple 15 projecting from the stationary end wall 14 of the chamber 12 and forms a rigid abutment for said stationary end wall, said end wall being preferably clamped fixedly to said portion 32 of the frame 23 by a nut 34 threaded onto the projecting end of the 110 nipple 15. If desired, the stationary end wall 14 may also carry a housing 35 to protect the flexible wall 13 from accidental injury.

Pivotedly mounted on the frame 23 at 36 120 is a fulcrum member 37 on which is pivoted at 38 a lever 39 which projects through the slot 40 of the member 7 and is suitably connected to said member 7, as by a pin 41. Lever 39 is provided with one or more adjustable weights which may be moved along the same and suitably clamped in adjusted position, two of such weights being shown at 42 and 43 respectively. Weighted lever 39 through its application of pressure to the 125

slotted member 7 on the valve stem 5, 6 is therefore adapted to close the valve 4 when the pressure within the chamber 12 is such that the weighted lever may collapse the 5 flexible wall of said chamber.

When the valve 4 is closed, the valve 19 is preferably operated to close the connection between the source of fluid under pressure and the chamber 12 and to vent the 10 interior of said chamber to the atmosphere. To effect simultaneous actuation of said valves, the valve 19 is preferably operated from the lever 39 and, to this end, is provided with a lateral arm 44 to which is pivoted at 45 an adjustable link 46 which, at its opposite end, is pivoted at 47 on the lever 39.

The parts are shown in the drawings as in the position which they assume when the 20 valves in the fuel and the pressure-fluid lines are closed. To open said valves the operator lifts the weighted lever 39, and this lever through its connection to the valve stem 5, 6 opens the valve 4, and through the link 46, 25 rotates the arm 44 and valve 19 to close the vent 22 and complete the connection from the conduit 18 to the interior of the chamber 12. The movable end wall 11 of chamber 12 is thereupon subjected to the pressure of the 30 fluid in the system with which the conduit 18 communicates, and assuming that the weights 42 and 43 have been so adjusted that they are balanced by the normal pressure in the chamber 12 acting on said movable end 35 wall 11, the weighted lever 39 will be held in its elevated position, and the valve 4 will be maintained open, by the pressure of the movable end wall 11 on the plate 10 connected to the slotted member 7 and valve stem 40 5, 6. If for any reason the pressure in the chamber 12 drops below normal, the weighted lever 39 overbalances the pressure on the movable end wall 11 and collapses the chamber 12, at the same time closing the valve 4 45 in the fuel line. Simultaneously with the falling of the weighted lever 39 it pulls on the link 46 to rotate the arm 44, and the valve 19 is moved to close the passage from the conduit 18 to the chamber 12, at the same 50 time bringing its passage 20 into register with the vent 22 and its passage 21 into communication with the passage 16. Thereupon the fluid in the chamber 12 is vented to the atmosphere, and so long as the chamber 19 remains in this position, super-atmospheric pressure cannot be built up in said 55 chamber. The parts will remain in this position until the operator again lifts the weighted lever 39 to open the valve 4 and restore communication between the source of 60 air under pressure and the chamber 12.

It will therefore be perceived that a safety device has been provided in which the flexible wall, which moves in response to variations of fluid pressure, is so related to means

directly connected to the fuel valve as to insure that the latter is positively closed when said flexible wall is actuated by a drop in the fluid pressure. At the same time means have been provided whereby said flexible 10 wall is rendered inoperative to open the fuel valve upon return of the pressure, insuring that the attendant must be present to light the burner before fuel is again admitted thereto, but without use of any detent or trip device which is likely to become worn or out of alignment. It will also be perceived that all of the time that the fuel valve is closed the fluid under pressure is excluded from the chamber so that the flexible wall does not 15 respond to fluctuations of pressure nor oppose the resetting of the device, and that this chamber is vented to the atmosphere all of the time that the fuel valve is closed so that there is no danger that leakage will 20 build up a pressure which will prematurely open the fuel valve.

While the present invention has been described in its preferred use, for which it possesses particular utility, it is to be understood that this safety device is capable of use in other relations wherein a fuel or other suitable valve is to be controlled by a suitable source of fluid under pressure. Moreover, while the embodiment of the invention illustrated on the drawings has been described with considerable particularity, it is to be expressly understood that the invention is not restricted thereto, as the same is capable of receiving a variety of mechanical 90 expressions, some of which will now readily suggest themselves to those skilled in the art, while certain features of the invention can be used without other features thereof, and changes may be made in the details of 95 construction, arrangement and proportion of parts, without departing from the spirit of this invention. Reference is therefore to be had to the claims hereto appended for a definition of said invention.

What is claimed is:—

1. In combination with a fuel conduit and a source of fluid under pressure, an axially movable seating valve in said conduit, a chamber having an axially flexible wall, a permanent direct connection between said wall and said valve, connections between said chamber and said source of fluid under pressure, means adapted to move said flexible wall and close said fuel valve upon a predetermined drop in said fluid pressure, a valve in said connections, and means operated by said means for closing said fuel valve for closing said valve in said connections.

2. The combination of a fuel conduit, a valve in said conduit, a chamber having a flexible wall adapted to control said valve, a conduit for conveying fluid under pressure to said chamber, a valve in said last-named

conduit adapted to close said conduit and open the interior of said chamber to the atmosphere, means adapted to move said flexible wall and effect the closure of said fuel valve upon a predetermined drop in pressure in said chamber, and means whereby said second-named valve is operated to close said pressure-fluid conduit and opens said chamber to the atmosphere upon closure of said fuel valve.

3. In combination with a conduit for conveying fuel and a source of fluid under pressure to aid in the combustion of said fuel, a valve in said fuel conduit, a chamber having a flexible wall adapted to control said valve, connections between said chamber and said source of fluid under pressure, means adapted to move said flexible wall and close said valve upon a predetermined drop in said

fluid pressure, and means for disconnecting 20 said chamber from said source of fluid under pressure and venting said chamber to the atmosphere upon the closure of said fuel valve.

4. In a safety device, the combination of 25 a valve, a chamber having a flexible wall adapted to control said valve, a conduit for conveying a fluid under pressure to said chamber, a valve adapted to close said conduit and vent said chamber to the atmos- 30phere, and means cooperating with said flexible wall to close said valves and vent said chamber upon a predetermined drop in pres- sure in said chamber.

In testimony whereof I have signed this 35 specification.

JEAN V. GIESLER.
